(57) **CLAIM**

An ornamental design for a retractable water flosser, as shown and described.

DESCRIPTION

FIG. 1 is a front view of a retractable water flosser in an extended state showing my new design;

FIG. 2 is a back view of the retractable water flosser in the extended state;

FIG. 3 is a first side view of the retractable water flosser in the extended state;

FIG. 4 is a second side view of the retractable water flosser in the extended state;

FIG. 5 is a top plan view of the retractable water flosser in the extended state;

FIG. 6 is a bottom plan view of the retractable water flosser in the extended state;

FIG. 7 is a perspective view of the retractable water flosser in the extended state;

FIG. 8 is a front view of the retractable water flosser in a retracted state;

FIG. 9 is a back view of the retractable water flosser in the retracted state;

FIG. 10 is a first side view of the retractable water flosser in the retracted state;

FIG. 11 is a second side view of the retractable water flosser in the retracted state;

FIG. 12 is a top plan view of the retractable water flosser in the retracted state;

FIG. 13 is a bottom plan view of the retractable water flosser in the retracted state; and,

FIG. 14 is a perspective view of the retractable water flosser in the retracted state.

The broken lines and surface shading shown in the drawings represent portions of the retractable water flosser that form no part of the claimed design.

1 Claim, 12 Drawing Sheets
